UNITED STATES PATENT OFFICE

NICHOLAS W. TRAUTNER, OF ST. PAUL, MINNESOTA

HUB REMOVING TOOL

Application filed August 23, 1929. Serial No. 387,918.

This invention relates to improvements in a hub removing tool and especially to means whereby the tool will maintain itself in operative position upon a hub while it is drawing the hub from a shaft.

It is my object to provide a device of the class described that is simple, compact, and inexpensive to manufacture, that is positive in operation and can be used with a minimum of effort.

In the accompanying drawing I have illustrated the form of hub and tapered shaft now embodied in a number of popular automobiles. In tools of this class it is important that the hub engaging element be prevented from moving laterally while the shaft engaging device is in operation. Where the quickly removable tools, such as those of the claw type, are employed it is distinctly advantageous to provide means for retaining the shaft retaining means in axial alignment with the shaft because the tool as a whole is otherwise freely removable laterally of the shaft and it is sometimes necessary to apply considerable force manually to maintain the tool in operative position. My device is so constructed that it can not get out of axial alignment as will be more clearly pointed out in the following specification and claims.

In the accompanying drawing, Figure 1 is a side elevation of my device in operative position upon a hub; Fig. 2 is a plan view of the same; Fig. 3 is a longitudinal section taken on the line 3-3 of Fig. 2, showing the manner in which the tool is placed in operative position; Fig. 4 is a plan view of an alternate form of my device and Fig. 5 is a longitudinal section taken on the line 5-5 of Fig. 4.

The preferred form of my device consists of a single casting 6 and a threaded thrust member 7 operating therein. A claw member 8 at one end of the casting is formed to fit a part of the periphery of a hub 9 back of and adjacent to an annular flange 10, integral with the hub. The other end of the casting 6 consists of a threaded bearing 11 adapted to receive the thrust member 7. Between the claw member 8 and the bearing 11, I provide an annular recess or keeper 12 in axial alignment with the bearing and thrust member

and of sufficient depth to receive the end of a shaft 13 protruding through the hub 9.

I have, for convenience, shown the device on the under half of the hub 9. It will be understood, however, that it can be operated in any position around the periphery of the hub.

To draw the hub 9 from shaft 13 with my device, it is first necessary to see that thrust member 7 is retracted in bearing 11 until it does not protrude into the keeper 12. The tool is then held at an angle of about 30° to the shaft as shown in Fig. 3. In this position the claw member 8 will slip past the flange 10 as the end of the shaft 13 is being inserted into keeper 12. The device will then be tilted to the position shown in Fig. 1 where the thrust member 7 and its bearing 11 are in axial alignment with the shaft. By the use of a wrench, the threaded member 7 is now extended into keeper 12 where it strikes the end of the shaft therein. This firmly locks the claw member 8 against the flange 10. Further extension of member 7 will draw the hub out of contact with the tapered shaft until it can be completely removed.

It will now be understood that when the thrust member is turned by a wrench a side pull develops against the thrust member which tends to throw the whole device off the hub. My invention prevents this since the keeper 12 encloses the entire protruding end of the shaft and holds the member 7 in axial alignment with the shaft at all times.

In Figs. 4 and 5, I have shown an alternate form which I have found especially adaptable to trucks. This form operates in the same way as the preferred form. It consists of a claw member 14, a bearing 15, a thrust member 16 threaded in said bearing, and an annular keeper 17 formed integrally with said thrust member. This form has no functional advantage over my preferred form but in larger sizes it can be made more compactly and economically as the annular keeper is included as a part of the thrust member rather than being made a part of the casting.

Having described my invention what I claim is new and desire to protect by Letters Patent is:

1. A tool for removing a hub from a shaft fitting within said hub comprising, a claw member on the inner end of the tool adapted to loosely engage the hub and having a side opening permitting lateral movement of the tool relative to said shaft, thrust means mounted on the outer end of the tool for engaging the outer end of the shaft, said thrust means being operable by the exertion of force directed laterally of the axis of said shaft and a keeper completely surrounding the periphery of the shaft to confine the outer end of the shaft against lateral movement free of said thrust means during the operation of the latter.
2. A tool for removing a hub from a shaft fitting within said hub comprising, a claw member on the inner end of the tool adapted to loosely engage the hub and having a side opening permitting lateral movement of said inner end of the tool relative to said shaft, a thrust screw threaded in the outer end of the tool for engaging the outer end of the shaft, said screw being disposed substantially coaxially with said shaft when in operative position and means extending across said opening for engaging the periphery of said shaft to confine the outer end of the tool against lateral movement free of the shaft when in operative relation to said thrust screw.
3. In a tool for removing a shaft from a hub having an annular shoulder, a substantially semi-circular claw member on the inner end of the tool adapted to loosely engage said shoulder and having a side opening permitting lateral movement of said end of the tool to and from engagement with the shoulder, a thrust screw threaded in the outer end of the tool and having a plain, flat inner end for engaging the outer end of the shaft and a keeper formed near the outer end of the tool to engage the periphery of the shaft on its side toward said opening when the tool is in operative position to thereby retain the outer end of the tool against lateral movement out of operative relation to said thrust screw when the latter is forcibly turned.

In testimony whereof, I have hereunto signed my name to this specification.

NICHOLAS W. TRAUTNER.
